(57) **CLAIM**

The ornamental design for a gun sight reticle, as shown and described.

DESCRIPTION

FIG. 1 is a view of a gun sight reticle as viewed through an eyepiece end of a riflescope;

FIG. 2 is a view of the gun sight reticle as viewed through an eyepiece end of a dual focal plane riflescope when the gun sight reticle is positioned at a second focal plane of a dual focal plane riflescope; and,

FIG. 3 is a perspective view showing an environment of use for the reticle of FIGS. 1 and 2.

In FIGS. 1-3 the interrupted lines indicate environmental features that form no part of the claimed invention.
